Primary Examiner — Kendra Leslie Hamilton*Assistant Examiner* — Elizabeth S Struble(74) *Attorney, Agent, or Firm* — Kilpatrick Townsend & Stockton LLP(57) **CLAIM**

The ornamental design for an orthosis as shown and described.

DESCRIPTION

FIG. 1 is a top, front right perspective view of an orthosis, showing my new design.

FIG. 2 is a top, front, left perspective view thereof.

FIG. 3 is a top, rear, left perspective view thereof.

FIG. 4 is a top, rear, right perspective view thereof.

FIG. 5 is a front elevation view thereof.

FIG. 6 is a rear elevation view thereof.

FIG. 7 is a left side elevation view thereof.

FIG. 8 is a right side elevation view thereof.

FIG. 9 is a top plan view thereof; and,

FIG. 10 is a bottom plan view thereof.

In the drawings, the equal-length broken lines depict portions of the orthosis that form no part of the claimed design.

1 Claim, 10 Drawing Sheets(56)
